UNITED STATES PATENT OFFICE

1,988,325

VENT SEAL

William R. Mobley, Miami, Fla.

Application March 28, 1932, Serial No. 601,550

4 Claims. (CL. 220—44)

My invention relates to a vent seal and has for its principal object the provision of a simple inexpensive means whereby the vent line from storage tanks for volatile liquids may be sealed 5 from the open atmosphere when the storage tank is not being filled or emptied, while at the same time the vent line, by reason of my invention, may perform its usual functions of admitting or discharging air when the storage tank is 10 emptied or filled.

Another object of my invention is to provide a device of the character described, having a capacity to hold a sufficient amount of liquid 15 to relieve the expansion and contraction of the contents of the storage tank or receptacle, by passing the liquid from one chamber to the other, thereby preventing the admission or discharge of air or vapor except when the tank is being filled or emptied.

20 A further object of this invention is to retain a desired pressure in the storage tank and discharge a portion of the air when such pressure is exceeded.

A further object of this invention is to prevent 25 loss of the contents of the storage tank by reason of excessive evaporation. It is the natural tendency of volatile liquids such as gasoline, to discharge heat in the form of vapor by process 30 of evaporation which causes considerable loss of the contents in storage through the conventional vent line. Such is the fact because the vent line communicates directly with the atmosphere and therefore permits the escape of the vaporized air in the storage tank. When a pressure lower than 35 that of the atmospheric is reached in the storage tank, because of the discharge of the lighter vapor the heavier unvaporized air is siphoned downward into the said storage tank until the pressure has been equalized. The repetition of 40 this natural phenomenon causes the constant circulation of air through the vent line and causes excessive evaporation.

A further object of my invention is to prevent 45 the introduction into the tank by means of an open vent of foreign objects and/or matter such as insects, dust, rain, sparks, water or vapor.

A further object of my invention is to prevent 50 the constant discharge of vapor from the tank, or the admission of air thereto by virtue of the expansion and contraction continuously going on therein because of the presence of a volatile fluid; thereby eliminating entirely, or at least 55 greatly reducing the fire hazard present in the conventional vent line, since a tank may not be ignited except through an opening communicat-

ing with the contents of said tank. As my invention eliminates all openings to and from the storage tank except when the tank is being filled or emptied, it is apparent that a tank equipped with my device could not be ignited under ordinary conditions.

With these and other equally important objects and advantages in view, the invention also resides in certain other new and useful features of construction and arrangement of parts which renders it more efficient in operation and less expensive to manufacture as will be apparent to those skilled in the art.

I accomplish the objects of this invention by a simple arrangement comprised of two separate 15 chambers, both of which are adapted to retain a liquid and communicate with each other below the top level of the said liquid, each of the said chambers being provided with separate openings. One of these chambers is provided with a connection by means of which it may be connected to the vent line of the storage tank. When the pressure is increased or decreased in the storage tank, the liquid is forced or sucked from one 20 chamber to the other, as the case may be, to admit or discharge air to equalize the said pressure. To provide for equalization of various pressures, the height of the chambers and the depth 25 of the liquid may be increased or decreased to cause the seal to break, and admit or discharge 30 air. Also the relative size or area of the chambers may be varied to cause the seal to break and discharge air at a higher pressure and to admit air at a lower pressure.

35 Referring to the accompanying drawing, I have shown for illustrative purposes only what now appear to be preferred forms of the invention. It is to be understood, however, that they are susceptible to considerable change and modification within the spirit and scope of the subject matter hereinafter claimed.

40 Figure 1 is a view partly in side elevation and partly in section illustrating a seal vent constructed in accordance with an embodiment of my invention.

45 Figure 2 is a view in top plan of the structure as illustrated in Figure 1.

50 Figure 3 is a view in top plan showing a modified form of Figures 1 and 2, by showing partitioned instead of cylindrical chambers as shown in Figures 1 and 2.

55 Figure 4 is a view partly in side elevation and partly in section illustrating a modification of seal vent constructed in accordance with an

embodiment of my invention as shown in other figures.

Referring particularly to the drawing and specifically to Figure 1, it will be observed that I have shown a container "1" provided with a cylindrical member "2", which is attached in air tight relation to the inner walls of the top of the container "1", as shown by the dotted lines in Figure 2, and terminating near the bottom 10 of the said container as shown in Figure 1, forming chambers "3", and "4". Each of the said chambers are provided with separate openings "5" and "6". The opening "6" is provided with a connecting means "7" (a lock nut being shown in this case) to which is connected a return bend formation "8" at the upper end of the vent line. The opposite end of which communicates with the storage tank (not shown). A liquid (preferably having a minimum evaporation) the level 15 of which is shown at "9", is retained within the container "1", partly filling the chambers "3" and "4". When the pressure is atmospheric in both chambers, the liquid levels will be the same, but when a sufficient pressure above or below 20 atmospheric is created in one chamber to pass a sufficient amount of the liquid from one chamber to the other, air will be discharged or admitted to equalize the said pressure.

In Figure 3, I have shown another form of the invention which is the same as Figure 1 and 30 2, except that I employ a partition which is attached to the inner walls of the container "1" in air-tight relation (as indicated by dotted lines in Figure 3) and extending downward, terminating 35 near the bottom of the said container "1", forming two chambers which function the same as chambers "3" and "4" of Figure 1. The space (as indicated by 12 in Figure 1) between the bottom of the container "1" and the partition or cylindrical member "2" shown in Figure 1, shall be of sufficient area to allow the liquid to be passed 40 readily from one chamber to the other. While in Figure 1, this space is shown by means of cutting away at 12, part of cylindrical member "2", communication between chambers "3" and "4" may 45 be established in any other way, and I may increase or diminish the size of the opening or the method of communication. It is desirable but not necessary that this last mentioned space be 50 opposite the vent "5". Thus any sudden pressure will cause the liquid to rise more rapidly opposite the opening "5" and prevent loss through opening "5". In Figures 2 and 3, the said opening "5" shown in Figure 1, is indicated by dotted lines. I may, under some conditions, find it 55 desirable to use a screen or other contrivance to prevent passage of anything other than vapor through opening "5".

Figure 4, is another form of the invention and 60 is substantially the same as Figure 1, except that pipes "10" and "11" perform the same function as openings "5" and "6" shown in Figure 1, respectively. I may also employ the opening "5" shown in Figure 1 in lieu of the pipe "10" shown 65 in Figure 4, or I may employ the pipe "11" shown in Figure 4 in lieu of the opening "6" as shown in Figure 1. The end of the pipe "11" is provided with a connection means "12", threads being shown for the purpose in this case whereby 70 it may be connected directly to the vent line in

a vertical position without the return bend formation "8" shown in Figure 1.

Without further description, it is thought that the features and the advantages of the invention will be readily appealed to those skilled in the art, and it will of course, be understood that changes in form, proportion and minor details of construction may be resorted to without departing from the spirit of the invention or its scope as claimed.

What I claim is:

1. A breather appliance for receiving from and returning to a body of volatile liquid those volatile gases which would otherwise be lost by variable temperature changes, said device consisting of a receiving chamber connected to a storage tank of such size as to store a substantial volume of vapor; and further comprising a second chamber and separate openings to each chamber, one of which openings communicates with the vent line of said storage tank and the other with the atmosphere, said chambers communicating with each other through a liquid at a point sufficiently below the level of said liquid so that said liquid produces sufficient head pressure to prevent the escape of vapors during the normal heating process of the normal day.

2. A breather appliance for receiving from and returning to a body of volatile liquid those gases which would otherwise be lost by changes in temperature, said device consisting of a receiving chamber, a second chamber, and separate openings to each chamber, one of which openings communicates with the vent line of a storage tank and the other with the atmosphere, both of said chambers being adapted to retain a liquid in their lower portions, and communicating with each other below the top level of said liquid at a point sufficiently below said top level so that said liquid produces a sufficient head pressure to prevent the escape of vapors during the normal heating process of the normal day.

3. A breather appliance consisting of separate chambers and separate openings to each chamber, one of which openings communicates with the vent line of a storage tank, and the other with the atmosphere; said chambers communicating with each other through a liquid at a point sufficiently below the level of said liquid so that said liquid produces a sufficient head pressure to prevent the escape of vapors during the normal heating process of the normal day.

4. A breather appliance for receiving from and returning to a body of volatile liquid those gases which would otherwise be lost by temperature changes, said device comprising a receiving chamber, a second chamber, and separate openings to each chamber, one of which openings communicates with the vent line of a storage tank, and the other with the atmosphere; said chambers communicating with each other through a liquid retained in the lower portion of one of the chambers, below the top level of said liquid at a point sufficiently below said top level so that said liquid produces a sufficient head pressure to normally prevent the escape of vapors, thereby precluding the admission or discharge of gas except when the tank is being filled or emptied.
